UNITED STATES PATENT OFFICE.

HERMAN R. TERHUNE, OF RIDGEWOOD, NEW JERSEY, ASSIGNOR TO SKEHAN & SWEENEY, INC., OF NEW YORK, N. Y., A CORPORATION OF NEW YORK.

DESIGN FOR A PRINTED FABRIC OR SIMILAR ARTICLE.

Application filed December 7, 1926. Serial No. 19,954. Term of patent 3½ years.

To all whom it may concern:

Be it known that I, HERMAN R. TERHUNE, a citizen of the United States of America, and a resident of Ridgewood, in the county of Bergen and State of New Jersey, have invented a new, original, and ornamental Design for a Printed Fabric or Similar Article, of which the following is a specification.

Reference is to be had to the accompanying drawing in which the figure is a view of a swatch of fabric showing the new design.

I claim—

The ornamental design for a printed fabric or similar article as shown.

HERMAN R. TERHUNE.
